COMBINED MERCHANTISING AND DISPLAY STAND

Lawrence Willard Patterson, 1415 W. 5th St.,
Santa Ana, Calif.

Filed Aug. 10, 1961, Ser. No. 66,296

Term of patent 14 years

(Cl. D80—9)

I claim:

The ornamental design for a combined merchandising and display stand, substantially as shown.
